UNITED STATES PATENT OFFICE.

ALBERT D. ROBINSON, OF LYNN, MASSACHUSETTS, ASSIGNOR TO GENERAL ELECTRIC COMPANY, A CORPORATION OF NEW YORK.

CONTROLLING AN ELECTRIC CANDY-SPINNING MACHINE.

No. 856,424.

Specification of Letters Patent.

Patented June 11, 1907.

Application filed September 6, 1905. Serial No. 277,149.

To all whom it may concern:

Be it known that I, ALBERT D. ROBINSON, a citizen of the United States, residing at Lynn, county of Essex, State of Massachusetts, have invented certain new and useful Improvements in Controlling an Electric Candy-Spinning Machine, of which the following is a specification.

This invention relates to machines for producing spun sugar candy, in which the granulated sugar is melted by an electric heater in a receptacle which is rotated rapidly by an electric motor. The molten sugar is thrown out of the receptacle by centrifugal force through small orifices from which it issues in the form of fine threads, which are caught and cooled in a bowl concentric with the rotating receptacle.

In order to avoid burning the sugar, or overheating the coils of the heater, or short-circuiting the heater when the heating receptacle is removed, it is necessary to start the motor before the heater circuit is closed, and to open the heater circuit either just before or at the same time with the motor circuit. If the heater circuit is controlled by a separate switch from the motor, there is danger that a careless operator may close it before starting the machine, or may leave it closed after he has stopped the machine.

The object of my invention is to prevent such an accident, and to this end it consists in the combination with a candy-spinning machine of the class described, of an organized system of circuits together with a peculiar switch for controlling them, as hereinafter set forth and particularly pointed out in the claims.

In the accompanying drawings, Figure 1 is a perspective view of an electric candy spinner; Fig. 2 is a diagram of the circuits, showing the switch in the running position; Fig. 3 is a detail view on a larger scale showing the brushes which convey current to the heater; Fig. 4 shows the switch turned to cut out the heater; the field coils and armature of the motor being in parallel; and Fig. 5 shows the switch turned to cut out the armature.

The general construction of the candy spinner is well known. In brief, it comprises a bowl 1 mounted on a pedestal 2 in which is an electric motor arranged with its armature shaft 3 passing up vertically through

the center of the bowl and carrying at its top 55 a small receptacle 4 for the sugar. The receptacle contains an electric heater to melt the sugar, which is thrown out by centrifugal force through the finely perforated walls of the receptacle when the motor is running. 60 The spun sugar collects in the bowl, from which it can be removed from time to time.

The conductors which convey current to the machine are attached to the binding-posts 5, 5', one of which 5 is connected by a 65 lead 6 with one terminal of the driving motor and also with one pair of the brushes 7, 7', which are supported on an insulating collar 8 secured to the pedestal, and make contact with one or two collector rings 9, 9' on the 70 stem 10 of the sugar receptacle. The collar 8 is concentric with the armature-shaft 3, and the stem 10 is made tubular so as to fit tightly on the upper end of said shaft. The heating coil 11, located in the receptacle, has 75 its terminals connected with the collector rings.

The driving motor is shunt wound, and one terminal common to both the field coils and armature coils, is connected with the lead 6. 80 The other terminals of said coils are connected respectively with two stationary two-armed contacts 12, 13, located concentric with the spindle 14 of a four-way switch located in the pedestal. The spindle projects 85 on the outside of said pedestal and has a handle 15 for manipulating it. An indicating dial, visible through a window 16 in the pedestal, shows the operator the position of the switch. The spindle carries two connected radial blades 17, 18 revolving in the plane of the arms *a* of the contacts 12, 13, and also three connected radial blades 19, 20, 21 insulated from the other two and revolving in the plane of the arms *b* of the contacts 90 12, 13. The blades in each set are preferably at right angles with each other; blade 17 being in line with blade 21, and blade 18 opposite to blade 20. Opposite the arm *b* of the contact 12 is a contact 22 which is connected by a lead 23 with the binding-post 5'; and opposite the arm *a* of the contact 13 is a stationary contact 24 connected by a lead 25 with a rheostat arm 26; the coils 27 of said rheostat being connected by a lead 28 with 95 the other pair of brushes 7', bearing on the collector ring 9'.

When the switch is turned so that neither

of the blades 19, 20, 21 is in contact with the contact 22, the circuit is open and the machine will not run. On giving the switch a quarter turn to the next position (Fig. 5) the 5 field coils of the motor are energized, but the armature is not in circuit. The next position of the switch (Fig. 4) cuts in the armature coils in parallel with the field coils, and starts the motor. The final position of the 10 switch (Fig. 2) cuts in the heater 11 in multiple with the motor. The current flowing through the heater can be regulated by moving the rheostat-arm 26 which projects through a slot in the pedestal. When the 15 switch is turned to cut out the motor, the heater also is cut out. It is thus impossible for a careless operator to burn out the heater, because he must cut it out before the motor can be stopped. Moreover, he cannot 20 unship the receptacle until he stops the motor, and thus he cannot get a short circuit through the brushes when both brushes bear on the lower collector ring 9, as they will for an instant during the operation of lifting the hub 25 10 off the shaft 3.

What I claim as new and desire to secure by Letters Patent of the United States, is,—

1. The combination with a power circuit and a heating circuit, of connected means for 30 first closing the power circuit and holding the heating circuit open until after the power circuit is closed; then closing the heating circuit, and then opening both circuits simultaneously.
2. The combination with a rotatable receptacle, of an electric motor for driving it, an electric heater for heating it, and means for insuring the starting of the motor before the heating circuit can be closed.
3. The combination with a rotatable receptacle, of an electric heater therein, an 40 electric motor for driving said receptacle,

and a single device for first starting the motor, then closing the heater circuit, and then opening both circuits simultaneously.

4. In a candy spinner, the combination with the driving motor and the heater, of means for insuring the starting of the motor before the circuit of the heater can be closed.

5. In a candy spinner, the combination 50 with the driving motor and the heater, of a single means for first turning the current on the motor and then turning it on to the heater.

6. The combination with a power circuit 55 and a heating circuit of a controlling switch therefor having a position wherein both circuits are interrupted, a second position wherein the power circuit is closed and the heating circuit open and a final position 60 wherein both circuits are closed.

7. In a candy spinner, the combination with the driving motor and the heater, of a single switch controlling both, and operating to start the motor before the heater is cut 65 into circuit.

8. In a candy spinner, the combination with the driving motor and the heater, of a switch and circuit connections whereby said motor must be started first, and then the 70 heater cut into parallel circuit therewith.

9. In a candy spinner, the combination with the driving motor and the heater, of a switch and circuit connections whereby current must be supplied first to the motor and 75 afterward to the heater, but the circuits of both will be opened simultaneously.

In witness whereof, I have hereunto set my hand this second day of September, 1905.

ALBERT D. ROBINSON.
